UNITED STATES PATENT OFFICE

165,883

GAS BURNER

Ralph Elroy Solomon, Roy Shelton, and Charles W. Agee, Chattanooga, Tenn., assignors to Samuel Stamping & Enameling Company, Chattanooga, Tenn., a corporation of Tennessee

Application June 30, 1950, Serial No. 10,852

Term of patent 7 years

(Cl. D81—10)

To all whom it may concern:

Be it known that we, Ralph Elroy Solomon, Roy Shelton, and Charles William Agee, all citizens of the United States, and each residing at Chattanooga, in the county of Hamilton, and State of Tennessee, have invented a new, original, and ornamental Design for a Gas Burner, of which the following is a specification, references being had to the accompanying drawing, forming part thereof, in which:

Fig. 1 is a top plan view of a gas burner, showing my new design,

Fig. 2 is a side elevational view thereof, and

Fig. 3 is a left hand end view of Fig. 1 on a reduced scale.

Fig. 4 is a right hand end view of Fig. 1 on a reduced scale.

We claim:

The ornamental design for a gas burner, substantially as shown.

RALPH ELROY SOLOMON.
ROY SHELTON.
CHARLES WM. AGEE.
